UNITED STATES PATENT OFFICE.

ANDREW BALON, OF ELIZABETH, NEW JERSEY.

CAR-BRAKE.

SPECIFICATION forming part of Letters Patent No. 698,784, dated April 29, 1902.

Application filed November 1, 1901. Serial No. 80,721. (No model.)

To all whom it may concern:

Be it known that I, ANDREW BALON, a citizen of Austria-Hungary, and a resident of Elizabeth, Union county, New Jersey, have 5 invented a certain new and useful Improved Car-Brake, of which the following is a specification.

This invention relates to a car-brake of novel construction and in which the brake-shoes are guided against the wheels in a positive manner.

In the accompanying drawings, Figure 1 is a side elevation of a car-truck provided with my improved brake; Fig. 2, a plan of one-half 15 of the same; Fig. 3, a detail of the brake-operating mechanism; and Fig. 4, a section on line 4 4, Fig. 3.

The frame of the truck is composed of an upper double section *a a'* and a lower double 20 section *b b'*, that converge toward their ends, so as to run out into a single front and rear section *c*. Between the two arms of the upper section *a a'* slides the load-carrying bolster *d*, guided by rails *d'* and supported upon 25 the center of a semi-elliptic spring *e*. The ends of this spring are coiled around pins *f'*, carried by links *f*, that are suspended between the arms of the lower section *b b'* at *f*. The space between the upper and lower sections 30 *a a'* and *b b'* is traversed by upright rails *g* for guiding the oil-boxes *g'*, which are supported by the axle-bearings. The car-truck frame is supported upon the oil-boxes by 35 springs *g*. The load is transmitted from the bolster *d* through the spring *e* to the lower frame-section and thence through rails *g* to the upper frame-section to be evenly distributed to the oil-box springs *g*.

To the inner side of the inner frame-sections *a a'* *b b'* is secured a plate *h*, provided with 40 three bearings *h*, *h'*, and *h*². The bearings *h'* receive upper and lower pins *i*, that project with their ends beyond the bearings. Upon these projecting ends are free to slide the 45 brake-shoes *j*, which are perforated to receive the pins. Springs *j'*, connecting the shoes at their upper and lower ends, tend to normally take them off the wheels *l*. The bearing *h*² receives the end of a squared shaft *k*, adapted to be operated by the brake-lever *k'* and 50 carrying an eccentric *k*², arranged between the pins *i*. When the brake is to be set, the shaft *k* is so turned that the eccentric *k*² bears against the shoes *j* and causes them to slide along the pins *i*, so as to engage the wheels *l*. 55 When the brake is to be taken off, the shaft *k* is turned to withdraw the eccentric *k*², when the shoes will be retracted by the springs *j'*.

What I claim is—

A car-brake provided with a bearing, an 60 upper and a lower pin received thereby and projecting with their ends beyond the bearing, spring-influenced perforated brake-shoes adapted to slide upon the projecting ends of the pins, and an eccentric that engages the 65 brake-shoes intermediate the pins, substantially as specified.

Signed by me at Elizabeth, Union county, New Jersey, this 25th day of October, 1901.

ANDREW BALON.
